S. ASHDOWN

LOGGING HOOK

Filed April 27, 1927

UNITED STATES PATENT OFFICE.

SYDNEY ASHDOWN, OF VICTORIA, BRITISH COLUMBIA, CANADA.

LOGGING HOOK.

Application filed April 27, 1927. Serial No. 186,912.

My invention relates to improvements in positive logging hooks more especially to keepers therefor, and an object of my improvement is to provide manually-operable means whereby a knobbed cable end is retained in positive engagement with the hook till release is desired when an easy adjustment of the keeper permits said release with a small length of cable slack.

I attain this and other objects of my improvement with the mechanism illustrated in the sheet of accompanying drawings, forming a part of this application, in which Figure 1 is a front side elevation of a choker hook with my keeper in place therein, Fig. 2 is an elevation of one edge of Fig. 1, Fig. 3 is an elevation of the other edge of Fig. 1, Fig. 4 is a cross sectional view of Fig. 2 on the line 4—4, Fig. 5 is a cross sectional view of Fig. 3 on the line 5—5, Fig. 6 is a longitudinal plan view of the keeper, Fig. 7 is a side elevation of Fig. 6, Fig. 8 is a front elevation of a bull hook with my keeper installed therein, Fig. 9 is a view of one edge of said bull hook, and Fig. 10 is a view of the other edge of said bull hook.

Similar characters refer to similar parts throughout. Certain parts are broken away to show other parts hidden thereby.

With more particular reference to the designated parts: The choker hook consists of two side pillars 11, 11 joined at the bottom by fixed jaws 12 having cable slot 15 therebetween and joined at the top by narrowing or approaching walls 13 terminating in lug 14 and reinforced at the bottom by low back wall 17.

On the inner or bearing surface of jaws 12 is recessed knob seat 16 preferably with a concave bottom. There are opposite transverse aligned holes 18 and 20 through pillars 11. The larger of these holes 18 has diametrical contiguous slots 19, 19. Hole 18 is surrounded by exterior annular boss 21 which defines recess 22 on the bottom wall of which are two inclined bosses a^{22} , a^{22} concentric with said hole.

Annular boss 23 encircles hole 20 defining recess 24.

Choker cable 25 with knob a^{26} fixed on the end thereof is shown as in slot 15 with said knob seated on jaws 12 in recess 16. The bearing end of said knob is preferably convex to fit in said concave seat.

Keeper shaft 27 has diametrical, longitudinal lugs or ribs 28, 28, bar-shape head 31

and cylindrical enlargement 30 between said head and lugs. It also has pin hole 29 near its end. The keeper shaft is extended through holes 18 and 20 by causing lugs 28 to pass through slots 19. The end of the shaft protrudes in recess 24 when head 31 bears on the bottom of recess 22, and on this protruding shaft end is mounted coil spring 32 over which is placed washer 33 which is retained by pin 34 inserted in hole 29. Spring 32 is by construction long enough to react between said pin and the bottom of recess 24 to cause head 31 to have considerable frictional resistance with said recess bottom against being turned thereon.

The keeper is shown in full lines in operative position to retain knob 26 in engagement in the hook with one of lugs 28 proximate the top of said knob. By revolving head 31 through an angle of 90° to its dotted position at 31' in Fig. 1 said lug is moved to its dotted position at 28' when knob 26 may be moved by hand to its dotted position at 26' when its lower end is above the confines of recess 16 and it is free to be moved out of the hook. The reverse movements are used to engage said knobbed cable with the hook: With the keeper in its described dotted position said knobbed cable end is passed within the hook in the dotted position at 26' and then seated in its full-line position in recess 16. Then handle 31 is turned from 31' to its full-line position at 31 by revolving it in either direction through an angle of 90° and the cable is again positively engaged with the hook.

Enlarged shaft body 30 is mounted in hole 18 which is of greater diameter than the width of slots 19, as is also true of said enlargement 30, and therefore said hole may serve as a bearing for the keeper.

When in position to retain the knob in its seat the keeper handle is disposed between bosses a^{22} one of which it must mount and pass over in being turned to its dotted position to free the cable knob. To mount this boss requires additional compression of spring 32 and thus the presence of bosses a^{22} within the path of movement of the keeper head adds to the positiveness with which said keeper serves its purpose.

Cable sleeve 35 has lugs 36, 36 spaced to receive hook lug 14 between them. When thus assembled bolt 37 is extended through registering holes in the three lugs and retained in place with nuts engaged thereon.

Bolt 37 is preferably parallel with keeper 27 and provides a hinge between the sleeve and hook which allows of considerable conformity of the hook to the log when in operative position thereon.

Choker cable 25 is extended through sleeve 35 forming a loop to the left of Fig. 1 which is broken away for lack of space.

Figs. 8, 9, and 10 illustrate a bull hook to which my keeper is applied. This hook consists of shank 38, jaws 39, 39, eye lug 40, knob recess 41 on said jaws, annular boss 42 encircles the cavity or recess in which operates the keeper handle, inclined bosses a^{42} , a^{42} are on the bottom of this recess to afford more positiveness to the keeper, annular boss 43 encircles the recess to house the keeper spring, the keeper shaft is shown at 44 and its two diametrical lugs at 45 and 46, and the keeper head at 47. The keeper-washer is at 48 and the retaining pin thereof at 49.

The other end of choker cable 25 shown in Figs. 1 and 2 is shown in Figs. 8-10 and has knob a^{25} fixed thereon. This knobbed cable end is shown as engaged in Figs. 8-10 where it is disengaged and reengaged in every way similar to that in the above described choker hook.

It is now apparent that the main object of my improvement,—to provide a modern logging hook which is positive in engagement with the work yet releasable therefrom by using a small length of cable slack, is very well attained by the use of the mechanism described.

In bull hooks the positive feature is of prime importance while the small slack requirement is less so, although at times it is very convenient indeed. But in choker hooks both features afford great advantages over hooks not possessing them. Because of frequent slackening in the hauling line choker hooks having slight engagement means frequently become disengaged during use. Also the slip noose encircling the log is often stubborn and difficult to loosen for the needed disengagement slack. While my hook has slight engagement means, making the slack requirements small to effect disengagement, the use of my keeper makes undesired disengagement impossible.

Having thus disclosed my invention, what I claim as new therein and desire to secure by Letters Patent is,—

1. A logging hook consisting of a bifurcated shank, **U** shaped jaws disposed on one end of said shank having a recessed seat thereon to engage the knobbed end of a cable when between said jaws, cable-engaging means disposed on the other end of said shank, a keeper shaft mounted for revolution across said shank distant from the end of said cable knob when on said jaw seat to permit the removal of said knob therefrom having a lug thereon to approach said knob ap-

proximately by turning said shaft and prevent the disengagement of said knob from said jaw seat and having a head thereon external to said shank for a finger hold, and a spring engaged with said shaft to react and cause said shaft head to frictionally engage with said shank.

2. A logging hook consisting of a bifurcated shank having a pair of aligned holes thereacross one of which has a radial slot contiguous therewith to permit the passage of a shaft lug therethrough, a fixed pair of **U**-shaped jaws disposed on one end of said shank having a recessed seat thereon to engage the knobbed end of a cable when between said jaws, cable-engaging means disposed on the other end of said shank, a keeper shaft having a head and a lug radial therewith extended through said holes for oscillation with said lug within said hook and said head external thereto said shaft distant from the end of said cable knob when on said jaw seat to allow removal of the knob therefrom and said lug approachable approximately to said knob top by turning said shaft to prevent the removal of said knob from the hook, and a spring engaged with said shaft for reaction to cause said shaft head to frictionally engage with said shank.

3. A logging hook consisting of a bifurcated shank having a pair of aligned holes thereacross one of said holes having radial slots contiguous therewith and inclined bosses on said shank concentric therewith also said shank having annular bosses surrounding said holes defining recesses in the sides of said shank, a fixed pair of **U**-shaped jaws disposed on one end of said shank having a recessed seat thereon to engage the knobbed end of a cable when between said jaws, cable engaging means disposed on the other end of said jaws, a keeper shaft having a head and lugs radial therewith extended through said holes for oscillation therein with said lugs within said shank, said head engageable with said inclined bosses in one of said shank recesses and one end of said shaft protruding in the other of said shank recesses, a coil spring in said other shank recess around said protruding shaft end, and engagement means on the end of said shaft to retain said spring while compressed to react and cause said shank head to bear on said inclined bosses to prevent free oscillation of said shaft.

4. A logging hook consisting of a bifurcated shank having a lug with a hole therethrough integral with one end of said shank, a cable sleeve having lugs thereon with aligned holes therethrough parallel with the axis of said sleeve engaged with the said shank lug by a hinge bolt extended through the said holes in said lugs, **U**-shaped fixed jaws disposed on the other end of said shank having a recessed cable knob seat to engage

the knobbed end of a cable when between said jaws, and a keeper shaft having a head and a lug thereon mounted for oscillation parallel with said hinge bolt in holes across 5 said shank with said head outside of said shank and said lug inside thereof said shaft distant from said cable knob when engaged with said jaws to permit the disengagement thereof said shaft lug approaching approximate to said knob by the oscillation of said 10 shaft to retain said knob in engagement with said jaws.
